UNITED STATES PATENT OFFICE

2,668,297

FLUSH TANK VALVE

Frank S. Reed, Florence, Ky.

Application August 8, 1950, Serial No. 178,189

3 Claims. (Cl. 4—57)

1

This invention relates to a flush tank valve and more particularly to means for centering the bulb valve on its seat. The ordinary or conventional flush tank construction embodies a rubber bulb serving as the flush water cut-off valve which seats itself on the outlet neck and is actuated by manually controlled trip means. In order for the bulb to function properly it is necessary that the guide for the stem of the valve be comparatively free acting, which often causes the bulb valve to seat improperly preventing complete cut off of the water.

My invention is directed primarily to improved guiding means for the bulb valve providing freedom of movement of the valve with accurate seating of the valve as it engages its seat.

The object of my invention is to provide a free acting guide for the valve which will definitely center the valve bulb on its seat.

My invention will be further readily understood from the following description and claims, and from the drawings, in which latter:

Fig. 1 is a fragmentary vertical sectional view showing a flush tank equipped with my improved valve guide.

Fig. 2 is a plan view of the valve guide.

Referring in detail to the drawings the numeral 11 indicates a flush tank, 12 an outlet neck including a valve seat 13 engaged by a bulb type valve 14. An overflow pipe 15 connects with the outlet neck 12 below the valve seat 13 and carries the usual guide bracket 16 for the valve stem 17, which is connected in the usual manner with the valve operated mechanism 18. The stem 17 is threaded into a fitting 19 molded into the top of the valve 14.

My improved guide means comprise a snap ring 20 arranged to snap around the neck 21 of the valve. Three arms 22 equiangularly spaced extend upwardly from the snap ring. A central guide member 23 having a central aperture 24 sliding on the stem 17 is also provided with extensions 25 to which beaded chains 26 are attached, with the ends of the chains received in slots 27 in the upper ends of the arms 22. The arms 22 are equally spaced from the axis of the

2

valve and when the valve is seated the guide 23 is slightly above the top of the valve for accurately seating the valve on its seat. When the valve is lifted by the operating mechanism, the chain connection permits the guide 23 to rise with the valve permitting free movement of the valve. As the valve drops the guide 23 will accurately seat the valve on its seat.

Having thus fully described my invention, what I claim as new and desire to secure by Letters Patent, is:

1. In combination with a flush tank valve, a guide stem extending upwardly from said valve, a guide for said stem, a frame having three equiangularly spaced arms extending upwardly about said valve, a second guide slidable on said valve stem, and chains connecting said second guide with the upper ends of said arms for centering said valve.
2. In combination with a flush tank valve, a guide stem extending upwardly from said valve, a guide for said stem, a snap ring engaging the valve fitting, three arms equiangularly spaced extending upwardly from said snap ring, a second guide member slidable on said stem, and chains connecting said second guide member to said respective arms.
3. In combination with a flush tank valve, a guide stem extending upwardly from said valve, a guide for said stem, a snap ring engaging said valve fitting, three arms equiangularly spaced extending upwardly from said snap ring, a second guide member slidable on said stem, and bead chains connecting said second guide member to said respective arms.

FRANK S. REED.
